MUD SAVER OR BOX

Harlan C. Welch, Jennings, La.

Application July 8, 1935, Serial No. 30,383

5 Claims. (Cl. 166—16)

The invention relates to a mud box and more especially to a mud saver for use in oil drilling rigs.

The primary object of the invention is the provision of a device of this character, wherein the same is supported by a derrick which is mounted for adjustment in a novel manner so that the mud box can be brought into position about a drilling stem of a well drilling rig of the rotary type used for drilling oil wells and in this position the mud on the separation of the drilling stem as collected from the well will be spilled in the mud box for flow therefrom to a mud pit, thereby eliminating a large quantity of the mud being lost and spilled upon the floor at the ground level with respect to said well.

Another object of the invention is the provision of a device of this character, wherein the same is mounted in such a manner on the drilling rig floor that it may be brought into use at any time as may be required and when not in use may be lifted from its operating position and set aside out of the way, it functioning as a mud saver when disconnecting a drill stem while removing or pulling the same out of a well or a hole as ordinarily a large quantity of mud is lost and spilled over the floor.

A further object of the invention is the provision of a device of this character, which is comparatively simple in construction, readily and easily handled, thoroughly reliable and efficient in its operation, assuring the saving of drilling mud, strong, durable, readily and easily set in operative position and removed at will and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a fragmentary elevation of a drilling stem of an oil drilling rig of the rotary type showing the device constructed in accordance with the invention applied thereto and the same being partly in elevation and partly in section.

Figure 2 is a horizontal sectional view through the drilling stem showing the device in top plan as applied thereto.

Figure 3 is a sectional view on the line 3—3 of Figure 1 showing by full lines the operative position of the box and by dotted lines a partially opened position thereof.

Figure 4 is a fragmentary elevation in detail of the latch adjuncts.

Similar reference characters indicate corresponding parts throughout the several views in the drawings.

Referring to the drawings in detail, A designates generally a portion of a drilling stem of an oil drilling rig of the rotary standard type and includes a separable joint coupling B about which is adapted to be placed the mud box constituting the present invention and hereinafter fully described.

The mud box or saver comprises a cylindrical body formed with half cylindrical sections 10 and 11, respectively, and this body has the top and bottom closed ends 12 excepting for a center opening 13 providing a space for the drilling stem A when the sections 10 and 11 are brought together and encircle the said stem. These ends 12 are similar to each other and carry suitable packing rings 14 to effect a fluid tight joint when the box is encircling the stem as is shown in Figures 1 and 3 of the drawings. The packing rings 14 are set into the ends 12 and extend into the openings 13 therein to make contact with the stem A entirely about the same. The ends 12, which are in half sectors, are made fast to the sections 10 and 11 by fasteners 15 and these sectors meet each other on the closing of the sections 10 and 11 about the stem A for the fitting of the box thereto to enclose the joint B so that on separation of the stem it can trap the mud as pulled from the well or hole drilled by the drilling rig and spill into the box to be caught thereby.

The box including the sections 10 and 11 is carried by a derrick which is formed with a tubular upright or post 16 having a right angular upper brace arm 17, it being joined with the section 10 near the upper end thereof and this arm is of hollow formation communicative with the post or upright 16 while opening into the box through the section 10 and joined therewith near its lower end is an inclined drain conduit or pipe 18, the same being extended from the post or upright 16 and opens into the same so that mud spilled within the post will be drained therefrom through the conduit or pipe 18 into the post or upright 16 whence it can be delivered into a mud pit closed at its upper end by a flooring 19 upon which is arranged the mount hereinafter described for the derrick.

The mount comprises a bed plate 20 having an elliptical shaped opening 21 centrally therein and this opening is common to an opening 22 matching therewith in the flooring 19. Rising from the

plate 20 at opposite sides of the opening 21 are spaced pairs of bearings 23 having rotatably fitted therein horizontally arranged adjusting screws 24 carrying shiftable trunnion bearings 25 for trunnions 26 extending from diametrically opposite sides of a tubular hub 27 fitted with antifriction bearings 28 encircling the upright or post 16 which is rotatably supported within said hub 27. The hub by the trunnions 26 can be swung while the bearings 25 for the trunnions can be shifted to transfer the upright or post 16 longitudinally with the extent of the opening 21 in the plate 20. In this manner the derrick will properly locate or position the box with relation to the drilling stem A to have it align therewith and properly embrace the same when fitted thereto.

The hub 27 has at diametrically opposite points ears 29, these carrying set screws 30 which regulate the tilt of the said hub and hold the same in the adjusted tilted position desired. These set screws 30 act against the plate 20 on adjustment thereof.

The meeting edges of the sections 10 and 11 carry suitable packings 31 and 32, respectively, to effect a fluid tight joint at these meeting edges when the sections 10 and 11 have been closed about the drilling stem A.

Exteriorly of and carried by the sections 10 and 11 are hand grips 33 for the manual opening and closing of the sections 10 and 11 and the handling of the mud box.

Upon the section 10 are keepers 34 for engagement with cam operated releasable latches 35, these being fixed to a turning arbor or axle 36 common to both the said latches and having fitting with the eccentrics 37 journaled in bearings 38 on and projecting from the section 11. The axle or arbor 36 has mounted thereon coiled tensioning springs 39 which operate to urge the latches 35 into latching engagement with the keepers 34, the arbor or axle 36 being fitted with a hand loop 40 for manual turning thereof so that the latches 35 can be disengaged from the keepers 34 when it is required to release the box from the drilling stem A and in this releasing the section 11, which is swung upon a pivot hinge 41 joining it with the section 10, moves outwardly away from the said section 10 and thus by the turning of the derrick the box can be moved to an inactive position or out of the way with relation to the drilling stem A. This derrick enables the convenient placing of the mud box in working relation to the stem A without excessive labor on the part of a user of the box and also by adjustment of such derrick the box can be properly aligned with the stem. As has been stated, on separation of the stem at the joint B the mud spilled therefrom will be trapped in the box and such mud drained through the conduit or pipe 18 into the mud pit beneath the flooring 19 covering the same.

The packing 32 when the sections 10 and 11 are latched closed with relation to each other will afford a seal at the latching side of these sections 10 and 11 when brought together at the meeting edges thereof. The trap of the mud as raised by the stem A from the well or hole within the box will prevent the spilling of the mud upon the flooring at the ground line with respect to the upper open end of the well or hole.

A mud saver constructed in accordance with the invention saves approximately ninety per cent (90%) of the drilling mud that is pulled out of the hole in the drill stem and wasted on the floor and on the ground while making trips.

If artificial mud, such as Baroid, Aquajell, or any kind of artificial mud is being used, and all that is being used can be kept within the hole and slush pits, it means less mud will have to be bought and mixed. The saving of this mud means saving dollars for the buying of the mud, and also means saving dollars for the mixing of this mud, which in any way saves time and labor.

If a company uses a mud saver, it speeds the worker to a great extent, as there is no mud spilt over or on the derrick floor. That means the worker will have dry tools to work with and a dry floor to work on; it also means he can pick up the tools with dry gloves and in lots of cases will keep junk out of the hole by this method.

It is a well-known fact and the nature of each and every man to dislike a mud bath and by using a mud saver there will be no mud baths, which many times cause serious accidents. Each and every man will run out of the reach of flying mud, sometimes running into his fellow workman, sometimes into some machinery that is being used, or maybe he will slip and fall, breaking a limb, which causes a loss time accident, lots of suffering to him, and maybe costs his life. By using this mud saver, most of these hazards will be overcome. It is estimated that a mud saver will pay for itself on one well.

The mud saver is not only adaptable for use in the drilling of oil wells but also in water wells or the like. The true purpose is to save drilling fluid, such as drilling mud, water or any kind of drilling fluid used in drilling water or oil wells. The mud saver is to be used on a rotary drilling rig and is usable when pulling the drilling stem or pipe out of the hole or well.

It should be apparent from Figure 1 of the drawings that the device is adapted to be attached to or for placing around a drill pipe at the connection or joint to catch the drilling fluid in the drill pipe when the joint is disconnected or unscrewed and such device having a drain allows the drilling fluid to be conducted to a predetermined place or location.

What is claimed is:

1. In a mud box a two-part hinged cylindrical body for embracing a drilling stem, a derrick carrying said body and having a drain leading therefrom, a mount for the derrick to permit shifting of the same and tilting thereof for correct alignment of the body with the drilling stem and a hub in said mount and rotatably supporting the derrick.

2. In a mud box a two-part hinged cylindrical body for embracing a drilling stem, a derrick carrying said body and having a drain leading therefrom, a mount for the derrick to permit shifting of the same and tilting thereof for correct alignment of the body with the drilling stem, a hub in said mount and rotatably supporting the derrick and means for latching the two parts of the said body in embracing relation to the drilling stem.

3. In a mud box a two-part hinged cylindrical body for embracing a drilling stem, a derrick carrying said body and having a drain leading therefrom, a mount for the derrick to permit shifting of the same and tilting thereof for correct alignment of the body with the drilling stem, a hub in said mount and rotatably supporting the derrick, means for latching the two parts of the said body in embracing relation to the drilling stem and means for sealing the two parts of said body together and about the drilling stem to render said body fluid tight.

4. In a mud box a two-part hinged cylindrical body for embracing a drilling stem, a derrick carrying said body and having a drain leading therefrom, a mount for the derrick to permit shifting of the same and tilting thereof for correct alignment of the body with the drilling stem, a hub in said mount and rotatably supporting the derrick, means for latching the two parts of the said body in embracing relation to the drilling stem, means for sealing the two parts of said body together and about the drilling stem to render said body fluid tight and means included in the mount to sustain the tilt of the derrick and the adjusted position of shift thereof.
5. In a mud box, a two part hinged cylindrical body for embracing a drill stem, tubular arms secured to and opening to the interior of said body adjacent the upper and lower ends thereof respectively, a support for said body comprising a 5 tubular upright mounted for revolution on its axis, said arms secured to and opening to the interior of said upright, whereby material may drain through said lower arm to said upright, said upright having an opening in communication with 10 a storage receptacle, and means to adjust said upright to bring its axis into parallelism with a drill stem.

HARLAN C. WELCH.
